UNITED STATES PATENT OFFICE.

FRANK P. SOUDER, OF BRIDGETON, NEW JERSEY.

CAN-Straightening Means.

1,135,732.

Specification of Letters Patent.

Patented Apr. 13, 1915.

Application filed October 28, 1913. Serial No. 797,805.

To all whom it may concern:

Be it known that I, FRANK P. SOUDER, a citizen of the United States, and a resident of Bridgeton, Cumberland county, New Jersey, have invented certain Improvements in Can-Straightening Means, of which the following is a specification.

My invention relates to means designed for the purpose of straightening damaged cans of the type employed in preserving food stuffs such as fruits and vegetables; which device is more particularly designed for the restoration of the rim flanges, of what are known as "sanitary cans", to their original and proper shape and condition for the application of the covers. For this latter purpose, it is necessary that the flange shall present a true circle in a single plane surrounding the open end of the can. The machine which I have devised is designed to restore the battered or displaced rim flange to its original perfect condition. These and other features of my invention are more fully described hereinafter, reference being had to the accompanying drawings, in which:

Figure 1, is a sectional elevation on the line 1—1, Fig. 2, of a can machine embodying my invention; Fig. 2, is a sectional elevation on the line 2—2, Fig. 1; Fig. 3, is a plan view; Fig. 4, is a perspective view of a battered can with deformed rim, and Fig. 5, is a perspective view of such can after it has been straightened by my improved machine.

My improved machine includes a table or stand 1, preferably of heavy construction, which may be solid metal, if desired, supported by legs 2, which may be received into sockets 3 carried by the table, or otherwise constructed, as may be desired; such table being provided with an aperture 4 for the passage of the cans. Pivot to the table at 5 are sections 6 of a clamping device to embrace the cans; the top or upper edge 6^a of said clamp sections serving further as anvils upon which the flattening of the rim flange of the cans may be accomplished.

Carried by rods 7 which project through the table 1 is a forming head 8, with an operating handle 9 and a flanged die 8^a on its under side having an annular flat surface 10 to engage the rim flange of a can; the central portion of said flanged die being beveled externally so as to readily fit within the mouth of the can when brought down to straighten the rim flange of the same. Be-

low the table a shelf or support is provided to receive the can, which shelf may be carried by bolts 13, and is adjustable vertically. The bolts 13 carry cups 14 receiving springs 15 whereby said shelf is spring-supported and is free to yield during the operation of reshaping the rim flange of the can.

The rim-shaping die has sockets 16, to which the rods 7 are adapted, and these sockets have inner beveled surfaces 17 for engagement with the sides of the sections 6 of the clamping device; such engagement causing the latter to closely embrace the can, and the upper edges 6^a of the same providing the desired anvil against which the flat surface of the die will strike; the spring-supported shelf yielding under the force of the blow, and the clamp sections holding the can so that the wall of the same will not be displaced. The shelf is adjustable up and down for cans of various heights, and it will be understood, of course, that by changing the size of the clamps, cans of different diameters may be treated; the dieing member being similarly removable for the application of different size structures corresponding to the size of the cans.

The clamping sections 6 are provided with automatic separating means in the shape of a spring 18, which may be coiled and is disposed between the arms of same, as indicated in Fig. 3; the latter being socketed at 19 for the purpose.

Cans which are damaged by having their walls bent may be straightened with the aid of a mallet by placing them over the half-round anvil bar 20 carried by the table 1.

I claim:

1. The combination, with a table, of a vertically movable can support, a pair of clamping members embracing the can and forming positioning means, the upper edges of said clamping members forming an anvil, a shaping device adapted to engage the top of a can and press its rim or flange against the clamping members, guiding rods for said shaping device, and cams carried by said shaping device to engage the clamping members and press them against the wall of the can to insure the position of the latter when the shaping device contacts with said rim or flange.

2. The combination, with a table, of a vertically movable can support, a pair of clamping members to embrace the can, the

upper edges of said clamping members forming an anvil, a shaping device adapted to engage the top of a can and press its rim or flange against the clamping members, 5 guiding rods for said shaping device passing through the table, and cams carried by said rods to press the clamping members against the wall of the can before the shaping device comes into contact with its rim or flange.

10 3. The combination, with a table, of a cushioned can support, said table being apertured in line with said support for the reception of a can, can centering means mounted independently of the can support, said centering means forming an anvil, a shaping device adapted to engage the top of a can and press the rim flange of the same against the anvil of the centering means, 15 and fixed engaging means carried by said shaping device to close and hold the centering means around a can when the shaping device contacts with the same.

4. The combination, with an apertured 25 table, of an adjustable spring-supported can holder centrally mounted below said aperture, centering means for said can pivotally mounted on top of the table and forming an anvil, a vertically movable shaping device 30 adapted to engage the top of a can and press

the rim flange of the same against said anvil, and means for tightly closing the centering means around the can just before the shaping device is brought into contact with said can.

35 5. The combination of an apertured table, an adjustable can support mounted below said table in line with the aperture, depending rods carrying said can support, springs carried by said depending rods below said can support, can positioning means pivotally mounted on top of the table and forming an anvil, a shaping device adapted to engage the top of the can and press the flanges of the same against the anvil, guiding rods for said shaping device passing through the table, means at the upper ends of said guiding rods for closing the positioning means around a can just before the shaping device is brought into contact with the can, and a manipulating handle carried by said shaping device.

45 20 45 In testimony whereof, I have signed my name to this specification, in the presence of two subscribing witnesses.

FRANK P. SOUDER.
